KNOCK-DOWN SHOE FOR FURNACES

John J. Holub, Cicero, Ill.

Application July 24, 1937, Serial No. 155,425

1 Claim. (Cl. 285—211)

My invention relates to shoes, boots, and the like for furnaces and other air distributing apparatus.

In its present embodiment my invention is shown as especially adapted for installation at the outer shell or casing of a warm-air furnace or heater for connecting the return-pipe or conduit to the furnace shell. It will be understood, however, that the structure I have herein disclosed is equally applicable to air distributors other than warm-air furnaces and heaters.

The structure which I have invented is in the form of a hollow body, one portion of which body is of a rectangular cross-section and is usually horizontally disposed. The remaining portion of said body is of a cylindrical or substantially cylindrical shape in cross-section and merges into the rectangular portion, and said cylindrical portion is disposed with its axis oblique to and is inclined upwardly from the axis of the rectangular portion.

When an ordinary shoe or boot has been assembled at a factory it is quite cumbersome and occupies considerable space, and since there are usually two shoes or boots for each warm-air furnace it has heretofore been the practice, when shipping a complete outfit, to store some of the smaller parts or fittings inside these shoes or boots. When, however, a large quantity of shoes or boots are stored or shipped without other parts or fittings they occupy considerable cubeage so that only a relatively small number may be stored in a transport vehicle such as truck or railway freight car.

I have invented a shoe, boot, or the like that is of a knock-down character and the parts are made in such manner that a quantity of each part may be readily nested together for storage or shipment, with the result that a large quantity may thus be taken care of in a space of relatively small cubeage. The parts, which are preferably two in number, may be readily and quickly assembled when it is desired to use them and this operation may be done without the use of special tools or apparatus and performed by persons unskilled in the art.

The shoe or the like comprises generally two superposed sections, the upper section being an inverted U-shape with a substantially semi-circular extension formed integral with it and disposed oblique thereto, and the other or lower section is a substantially flat plate and a curved or semi-cylindrical portion disposed oblique to the flat plate. The margins of the two sections

are coincident with and substantially parallel to each other, and interengaging means are provided along the proximate edges of said sections whereby they are maintained in knock-down assembly. I have also provided means at the outer edge of the cylindrical extension for detachably connecting the lower end of the return pipe to the shoe.

In devising my improved shoe, boot and the like I have numerous objects in view. One of these objects is to provide a shoe or the like that is novel in construction; other objects are to provide a structure that is effective and dependable in performing its functions; which is made of sturdy but simple parts and is capable of withstanding severe usage; and which is economical to manufacture so that it may be sold for a reasonable retail price. Other objects and advantages of my shoe or the like will be obvious to persons skilled in the art after my invention is understood from the within disclosure.

I prefer to accomplish the numerous objects of my invention and to practice the same by means of a structure substantially as set forth in the following description and as more particularly pointed out in the appended claim. I now make reference to the accompanying drawing that forms a part of this specification.

In the drawing:

Figure 1 is a vertical side elevation of my invention showing the shoe installed upon the casing of a warm-air furnace or other air distributor.

Figure 2 is a view slightly enlarged showing the several parts in detached positions and about to be assembled.

Figure 3 is a transverse fragmentary section on line 3—3 of Figure 1 drawn to a full-size scale.

Figure 4 is a similar section taken on line 4—4 of Figure 1.

Figure 5 is another similar section taken on line 5—5 of Figure 1.

The drawing, it will be understood, is somewhat schematic for the purpose of illustrating a typical or preferred embodiment of my invention, and in said drawing like reference characters refer to like parts wherever these parts appear in the different views.

As hereinbefore stated the shoe or the like is a knock-down structure and for this purpose it is made in the several separable parts or sections. These separable parts or sections are designated in Figure 2 as A, B, and C. The shoe proper comprises the superposed sections A and B. The section C is a piece of cylindrical con-

ductor pipe 10 having an oblique lower edge that is provided with a bead 11 and a flaring annular flange 12, the latter adapted to be engaged inside and clamped by the beads 13 and 14 at the 5 adjacent or proximate edges of the respective sections A and B of the shoe as shown in detail in Figure 5.

The upper section A of the boot comprises a bent piece of sheet-metal the portion of which 10 that is nearest the furnace shell D being bent into an inverted U-shape with angular corners to provide vertical sidewalls 15 and a top wall 16. This portion of the shoe section is disposed upon a horizontal axis, and extending obliquely upward from the outer portion thereof is an extension that is substantially semicylindrical or 15 arcuate and identified as 17 in the drawing. The lower margins of the metal forming the section A of the shoe is provided with means that 20 interengage with the margins of the lower section B that are coincident with and parallel thereto. These means are S-shape in cross-section and are preferably a seam that is formed by bending the edge portion of the sheet-metal 25 back upon itself as shown at 18 in Figure 3 and then folding the remaining edge portion downward as shown in 19 of Figure 3 so that narrow channels 20 are provided at the lower edges of the top section to receive the margins of the lower 30 section B of the shoe. This formation, or means for interengaging the two sections of the shoe extends along both bottom edges of the U-shaped portion and both bottom edges of the semi-cylindrical extension of section A.

35 The section B of the shoe, like the section above-described, is formed integral from one piece of sheet-metal. The portion of this section which is nearest the furnace shell comprises the horizontal bottom wall 21 that extends across 40 the open lower portion of the rectangular part of the upper section A to provide a closure therefor and at its margins this wall is provided with opposite upstanding flanges 22 that enter the channels 20 at the margins of the upper section. 45 The remainder of section B is arcuate and somewhat semi-cylindrical in form and is disposed oblique to the plane of the wall 21. The semi-cylindrical or arcuate portion is identified as 23 in the drawing. The longitudinal margins 24 of this portion of section B are substantially 50 straight and are interengaged with the channel 29 in the proximate margin of the semi-cylindrical part of upper section A.

As shown in Figure 3, after the upstanding flanges 22 have been inserted into the channel 55

20, the extreme outer edges of the bent-down portions 19 are folded or turned under and flat against the wall 21 as at 19a to maintain the rectangular portion of the sections A and B in assembly. The arcuate or semi-cylindrical walls of the sections 5 A and B, after the margins have been interengaged, are held in position by clamping bolts 25 that pass through the lateral portions of L-shape brackets 26 riveted to the respective walls of the cylindrical portion so that the walls are 10 drawn together by nuts 27 screwed on the threaded ends of the bolts 25. Prior to the drawing together of the arcuate portions of the sections A and B, the flared flange 12 of the pipe or elbow section C is placed in the interior channel 15 formed by the bead 13-14 in which position the pipe section C may be rotated upon its axis until its outer edge is in the position desired for the run of the return conduit. After this adjustment has been made the sections are clamped 20 together.

From the foregoing it will be seen that the section A and the section B when separate from each other are capable of having a plurality of the corresponding sections nested in each other for 25 compact storage and shipment. The structure may readily be knocked down by removing the bolts 25 and by straightening out the folded-under portion 19a in the manner shown in the dotted lines shown in Figure 3.

What I claim is:

A knock-down shoe and the like for furnaces adapted for assembly at the place of use, said shoe comprising a cylindrical wall member disposed in upstanding position, and a separable 35 member having detachable connection with the lower edge of said cylindrical wall member; said separable member embodying upper and lower wall sections having meeting edges in horizontal and oblique planes, said wall sections together 40 providing horizontal and oblique ducts the latter of which ducts communicates with the duct provided by said cylindrical wall member, and means for detachably securing said upper and lower wall sections together whereby the ends of the walls 45 of the oblique duct are detachably assembled with the proximate edge of said cylindrical wall member, one of said sections having a U-shaped channel at each side thereof receiving the adjacent edge of the other section, one side of said 50 U-shaped channel having an extension thereon in position to be turned over on an angular portion of the other section to secure said sections in assembled relation.

JOHN J. HOLUB. 55
